UNITED STATES PATENT OFFICE.

FRANCIS R. BURGESS, OF CHICAGO, ILLINOIS, ASSIGNOR TO AMERICAN FLANGE & MANUFACTURING COMPANY, OF CHICAGO, ILLINOIS, A CORPORATION OF ILLINOIS.

CONTAINER AND SEALING MEANS THEREFOR.

Application filed March 3, 1927. Serial No. 172,375.

My invention relates to containers which are provided with bungs in the form of threaded plugs which are received within the threaded interiors of bushings that are assembled with wall portions of the containers, the invention finding particular use in connection with barrels in which oil or other liquid is packaged for shipment.

The invention has for its object the provision of means for obstructing undetectable access to and removal of the plugs. To this end I employ a sealing device or guard assembled with a container wall and positioned to prevent undetectable access to the plug, which usually has a tool engaging formation upon its outer end, access to which is obstructed by the guard.

In the preferred embodiment of the invention, the guard is in the form of a hood which completely covers the otherwise exposed outer end portion of the plug so that not only is access to the tool engaging formation of the plug guarded against but access of other dislodging tools such as chisels and punches is also guarded against. In the preferred embodiment of the invention, the guard or hood is clamped in a space between the container wall and a flange that is provided upon the outer end portion of the plug. The bushing is desirably also provided with a flange that is located in this space, the guard or hood being clamped between the flanges upon the plug and bushing.

The invention will be more fully explained in connection with the accompanying drawing in which Fig. 1 is a view illustrating the preferred embodiment of the invention, the bushing and a portion of the container wall being shown in section while the plug and the guarding or sealing device that protects its outer end are shown in elevation; Fig. 2 is a plan view of the structure shown in Fig. 1; Fig. 3 is a sectional view on line 3-3 of Fig. 1; and Fig. 4 is a view on a larger scale of a portion of the structure, partly shown in elevation and partly in section.

The container, such as a barrel, has one wall 1 thereof formed with a depending rim 2 which surrounds a circular hole formed through this wall. An interiorly threaded bushing 3 is snugly received within this hole and is closely surrounded by said rim, this bushing being shown with an

outwardly curled inner edge portion 4 which grips the inner edge of said rim 2 and a circumscribing flange 5 which is tightly seated upon the wall 1, this flange desirably lapping this wall on the exterior of the container. The closure plug 6 is screwed within the bushing 3 and is formed with a circumscribing flange 7 which laps the flange 5 and wall 1, an annular sealing gasket 8 being desirably interposed between the flanges to render the joint between the plug and bushing fluid-tight. The outer end of the plug is formed with two tool engaging formations, one in the form of an enlargement 9 which is of hexagonal or polygonal exterior contour, and the other in the form of a recess 10 extending through the enlargement 9 and into the body of the plug, this recess being of square or other contour to receive a wrench having a plug formation snugly receivable within and corresponding in shape to said recess.

The sealing device or guard of my invention is preferably in the form of a hood comprising a body or skirt portion 11 which has a part that is inwardly turned at its inner end and confined between the gasket 8 and the bushing flange 5, this hood body or skirt being preferably firmly clamped in position when the screw plug is driven home, the portion of the body between the flanges upon the plug and bushing being tightly clamped between these two flanges. Said hood also includes a cap portion 12 which is not initially assembled or fully assembled with the body or skirt portion 11, the closure plug being tightly applied before the cap is finally assembled to enclose the plug portions 7, 9. The outer annular edge of the skirt portion 11 of the guard or seal may be initially hook shaped in cross section, as indicated at 11' at Fig. 4. The cap portion 12 may be provided with an annular hook portion 12' that is enmeshed with the hook portion 11' after the plug 6 has been firmly seated, a suitable tool being employed for so thoroughly incorporating the hook portions 11', and 12', together that the cap portion 12 can not be removed without the removal being detectable.

All of the plug upon the exterior of the container is thoroughly guarded from undetectable access by the construction described. The bushing 3 and its flange 5 surround the portion of the plug that is in their

zone. The sealing member, 11, 12, protects all of the plug in the outer zone adjacent to the flange 5. The material of which the hood is made is desirably very thin sheet metal such as tin which will readily tear or become ruptured if any attempt is made to loosen the plug as by means of wrenches applied to the plug flange 7 or the plug enlargement 9.

10 The cap portion 12 of the hood may have a circumscribing ledge 12² between its body portion and its hook portion 12¹. This ledge may be formed with identifying indentations 12³ which receive corresponding formations upon the outer annular edge of the body portion 11 of the hood.

15 Preventing undetectable access is referred to in the claims in the sense that access which is sufficient to permit of the effective engagement of a dislodging tool with the plug is guarded against.

Changes may be made without departing from the invention.

20 Having thus described my invention, I claim:

25 1. The combination with a container formed with a hole through a wall thereof; of an interiorly threaded bushing assembled with said wall in alignment with said hole, said bushing having a circumscribing flange which laps the wall where the wall surrounds said hole; a closure plug screwed within the bore of the bushing; and a hood assembled with said container wall by said flange and covering the outer end of said plug to prevent undetectable access thereto.

30 2. The combination with a container formed with a hole through a wall thereof; of an interiorly threaded bushing assembled with said wall in alignment with said hole, said bushing having a circumscribing flange which laps the wall where the wall surrounds said hole; a closure plug screwed within the bore of the bushing and having a tool engaging formation upon its outer end; and a hood comprising a body portion assembled with said container wall by said flange, and a cap portion joined with said body portion and covering said tool engaging formation to prevent undetectable access thereto.

35 3. The combination with a container formed with a hole through a wall thereof; of an interiorly threaded bushing assembled with said wall in alignment with said hole, said bushing having a circumscribing flange which laps the wall where the wall surrounds said hole; a closure plug screwed within the bore of the bushing; and a guard comprising a body portion assembled with said container wall by said flange, and a portion joined with said body portion and covering the outer end of said plug to prevent undetectable access thereto.

40 4. The combination with a container

formed with a hole through a wall thereof; of an interiorly threaded bushing assembled with said wall in alignment with said hole, said bushing having a circumscribing flange which laps the wall where the wall surrounds said hole; a closure plug screwed within the bore of the bushing, said closure plug having a flange lapping the flange of the bushing; and a hood having a skirt portion confined between said flanges and covering the outer end of said plug to prevent undetectable access thereto. 79

5. The combination with a container formed with a hole through a wall thereof; of an interiorly threaded bushing assembled with said wall in alignment with said hole, said bushing having a circumscribing flange which laps the wall where the wall surrounds said hole; a closure plug screwed within the bore of the bushing, said closure plug having a flange lapping the flange of the bushing; and a hood comprising a body portion having a part confined between said flanges and a cap portion joined with said body portion and covering the outer end of said plug to prevent undetectable access thereto. 80

6. The combination with a container formed with a hole through a wall thereof; of an interiorly threaded bushing assembled with said wall in alignment with said hole; a closure plug screwed within the bore of the bushing, said closure plug having a flange lapping said bushing; and a hood having a skirt portion confined between said flange and wall and covering the outer end of said plug to prevent undetectable access thereto. 85

7. The combination with a container formed with a hole through a wall thereof; of an interiorly threaded bushing assembled with said wall in alignment with said hole; a closure plug screwed within the bore of the bushing and having a tool engaging formation upon its outer end, said closure plug having a flange lapping said bushing; and a guard comprising a body portion having a part confined between said flange and wall and a portion joined with said body portion and covering said tool engaging formation to prevent undetectable access thereto. 105

8. The combination with a container formed with a hole through a wall thereof; of an interiorly threaded bushing assembled with said wall in alignment with said hole; a closure plug screwed within the bore of the bushing, said closure plug having a flange lapping said bushing; and a hood comprising a body portion having a part confined between said flange and wall and a cap portion joined with said body portion and covering the outer end of said plug to prevent undetectable access thereto. 120

9. The combination with a container 125

formed with a hole through a wall thereof; of a closure plug within said hole, said closure plug having a flange lapping said wall; and a hood having a skirt portion confined 5 between said flange and wall and covering the outer end of said plug to prevent undetectable access thereto.

10. The combination with a container formed with a hole through a wall thereof; 10 of a closure plug within said hole, said

closure plug having a flange lapping said wall; and a hood comprising a body portion having a part confined between said flange and wall and a cap portion joined with said body portion and covering the 15 outer end of said plug to prevent undetectable access thereto.

In witness whereof, I hereunto subscribe my name.

FRANCIS R. BURGESS.
